STARTING FILTER FOR HYDRAULIC PUMPS

Harold K. Ihrig and Eugene O. Layman, Oklahoma City, Okla., assignors to Kobe, Inc., Huntington Park, Calif., a corporation of California

Application July 26, 1947, Serial No. 763,926

14 Claims. (Cl. 103—46)

1

This invention relates to the fluid-operated pumping art, and, more particularly, to a fluid-operated pumping device adapted to be disposed in a well to safeguard the operation of a fluid-operated pump also disposed in the well.

Conventional fluid-operated pumps include a fluid-operated engine coupled to a pump mechanism in turn adapted to pump well fluid from a well upwardly to the surface of the ground. In such units, oil or other operating fluid under relatively high pressure is conveyed downwardly to the fluid-operated pump through a power tubing to operate the pump. Occasionally it is necessary or desirable to remove the pump from the well for inspection, repair, or replacement, in which case it is necessary to pull the power tubing and stand or hang it in the well derrick. The operating fluid employed to operate such a fluid-operated pump is relatively clean, being usually filtered or settled, but nevertheless frequently contains a small amount of corrosive water and may also contain finely divided solids in the form of fine sand or iron compounds which may be classed as iron oxides. Such iron compounds frequently are magnetic in character, and tend to accumulate on the inner wall of the power tubing and in the coupling recesses between sections of the tubing. Fine sand, if present, is also frequently caught with the iron oxide, particularly if the operating fluid contains some wax, or paraffin, dissolved or entrained which deposits on the tubing wall. The corrosive water present in the operating fluid frequently corrodes the inner surface of the power tubing, forming an iron oxide scale. When the power tubing is removed from the well, the shocks and jars to which it is subjected during the removal process tends to loosen the deposits formed in the tubing, particularly the deposits formed in the coupling recesses between sections of tubing. Also, when the tubing is standing in the derrick it tends to accumulate additional dust and dirt, and is further attacked by corrosion due to the combined effects of oxygen from the atmosphere and the salt brine left in the tubing by the operating fluid while in use. Even though the amount of corrosive, or salt, water in the operating fluid may be only 1 percent or less, it normally causes considerable corrosion and scaling on the inner wall of the power tubing.

The fluid-operated pump, or a replacement therefor, is normally re-run into the well with the original tubing, and when in operating position the power tubing is again filled with operating fluid, the operating fluid being passed down-

2

wardly through the tubing to the pump. This process of re-filling the power tubing washes a substantial part of the accumulation of iron oxide and other foreign materials accumulated therein to the bottom thereof, or directly to the top of the fluid engine of the fluid-operated pump. When the flow of the operating fluid through the power tubing and through the pump commences, obviously, it carries with it a high concentration of such foreign materials which are highly detrimental to the fluid-operated engine of the pump, causing substantial wear and thus shortening the life of the engine parts, and sometimes, if in sufficient quantity, causing the engine to stick and score on its first few strokes. As will be apparent, the amount of such foreign material in the operating fluid is greatest at the starting of the operation of the fluid-operated pump, and declines substantially after the pump has been in operation a few minutes or hours, depending upon the production rate at which the fluid-operated pump is operated. Thus, if the fluid-operated pump continues to operate without damage until this critical starting period is past, the amount of foreign material in the operating fluid decreases to a point at which it is not normally harmful to the continued operation of the pump and subsequent long pump life can normally be expected. However, a relatively high percentage of fluid-operated pumps fail to start or are substantially damaged due to the initial high concentration of foreign material in the operating fluid when operation is recommenced.

It is a primary object of the present invention to substantially obviate and reduce the difficulties mentioned above, by preventing an initial flow of operating fluid to a fluid-operated pump from carrying with it to the pump harmful foreign materials. We prefer to accomplish this by providing suitable filter means between the power tubing and the fluid-operated pump which will filter most, if not all, of the solid foreign materials from the operating fluid until such time as the free solid foreign materials in the power tubing have been conveyed by the operating fluid to the lower end thereof, and this is a further object of the invention. It is a further object of the invention to provide in connection with such a filter means a trap for collecting and retaining substantial quantities of sand and other solid foreign materials entrained in the operating fluid passing to the fluid-operated pump.

As the permeability of an effective filter for such use is relatively low, and is rapidly reduced

by the accumulation of foreign material, and as a filter of low permeability creates a substantial pressure drop in the fluid passing therethrough, which is undesirable, it is a further object of the invention to provide means whereby after a relatively short initial period of operation the filter means will be rendered ineffective, and a direct flow of operating fluid from the power tubing to the fluid-operated pump will be permitted. We prefer to accomplish this by providing a by-pass in parallel with the filter means, preferably in the form of a frangible plug, which is so designed that upon a predetermined rise in fluid pressure in the supply tubing the plug will be broken and thus permit a direct flow of operating fluid from the supply tubing to the fluid-operated pump. As will be apparent to those skilled in the art, the accumulation of foreign material on the filtering surface of a filter normally reduces the permeability of the filter element, tending to raise the fluid pressure on the input side of the filter. We prefer to design our by-pass means so that a predetermined accumulation of foreign material on the filter element will increase the fluid pressure in the supply tubing to a value at which it can open the by-pass means to permit such direct flow to the fluid-operated pump. By this provision, the opening of the by-pass means is rendered automatic after the initial charge of foreign material in the operating fluid is accumulated safely on the filter element or in the trap provided for such collection. It will be apparent, however, that the by-pass means may be opened at will by simply increasing the volume (which in turn increases the pressure drop across the filter), of the operating fluid delivered through the power tubing, which can be effectively controlled, if desired, from the surface of the ground at the source of the high pressure operating fluid, normally a triplex pump. This is an added feature of the invention.

Other objects and advantages of the invention will appear in the following specification and the drawing which is for illustrative purposes only, and in which:

Fig. 1 is a diagrammatic, utility view, partially in section, of my invention installed in a well;

Fig. 2 is an enlarged vertical sectional view of the upper end of a portion of the invention;

Fig. 3 is an enlarged vertical sectional view of the lower end of a portion of the invention, being a downward continuation of Fig. 2.

Referring to Fig. 1 of the drawing, we show a surface pump 10, which may be of any conventional type, such as a triplex, adapted to supply operating fluid, such as clean oil, under relatively high pressure to a power tubing 11. The power tubing 11 passes downwardly through a tubing head 12 and a production tubing 13 suspended from the tubing head and disposed in a well casing 14. The well casing 14 is provided with perforation 16 adjacent the lower end thereof to permit oil or other well fluid to flow from the producing formation around the well casing into the same.

Connected to the lower end of the power tubing 11 is a combined filter and by-pass unit 17, generally including a tubular shell 18 containing a by-pass element 19 and a filter element 20 secured in axial alignment and radially spaced from the inner wall of the tubular shell 18 so as to provide an annular space 21 therebetween and a trapping space 23 adjacent the lower end of the filter element. The lower end of the filter and

by-pass unit 17 is connected to the upper end of a fluid-operated pump 24, which may be of any conventional design, which in turn is seated in an inlet member 25 having a check valve element 26 therein, the inlet member providing communication between the interior of the well casing 14 and the inlet of the fluid-operated pump 24 and being supported by the lower end of the production tubing 13.

10 Referring to Fig. 2, the by-pass element 19 includes a tubular stem 28 having a screw plug 29 in the upper end thereof and provided with radial openings in the form of longitudinal slots 30. The lower end of the stem 28 is surrounded by a collar 31 which is threaded into a tubular coupling 32, the lower end 33 of the stem being flared and clamped between the collar and the coupling. The lower end of the tubular coupling 32 is threaded into a coupling member 35, and 15 clamped between the tubular coupling 32 and the coupling member 35 is an assembly comprising an upper annular ring 36, a washer 37, a blow-out disk 38 which constitutes a frangible plug, a lower annular ring 39 and a circular filter plate 40 having perforations 41 therein. The disk 38 is formed of soft metal, fibre, or other suitable material, and is proportioned so that it can be broken by a predetermined fluid pressure rise within the tubing coupling 32.

20 Threaded into the lower end of the by-pass element 19 is an upper collar 43 of the filter element 20, the collar in turn having the upper end of an upper liner 44 threaded thereto, the liner being provided with circumferentially spaced 25 radial ports 45 with which registers an annular upper filter member 46 carried on the upper liner 44. The lower end of the liner 44 is threaded into the upper end of a central collar 47. The upper filter member 46 is held in place by being 30 clamped at its upper end between the upper end of the liner 44 and the lower end of the collar 43, and by being clamped at its lower end between the lower end of the liner and the upper end of the collar 47.

25 Threaded into the lower end of the central collar 47 is the upper end of a lower liner 49 which is likewise provided with radial perforations 50 which are covered by a lower filter member 51 carried on the lower liner. The lower end of the lower liner 49 is threaded into a lower coupling 52, the upper end of the lower filter member 51 being clamped between the central collar 47 and the lower liner 49, and the lower end of the filter member being clamped between the lower coupling 52 and the lower liner 49. The filter members 46 and 51 may be of any suitable material, such, for example, as wool, ceramic material, or porous metal. Cotton or cellulose fibres are usually unsuited as filter material in our invention as such materials tend to deteriorate in the operating fluid at high bottom-hole temperatures, and in such case may allow accumulated foreign material on their exteriors to pass through the device into the pump weeks or months after starting, with the attendant disadvantages noted above. The lower end of the lower coupling 52 is connected to a nipple 53 which, as shown in Fig. 1, is adapted to be threaded into a connecting collar 54 connected to the upper end of the fluid-operated pump 24. As will be apparent, the nipple 53 and the collar 54 close the lower end of the tubular shell 18.

30 In operation, the device is installed in a well as illustrated in Fig. 1. Operating fluid under high pressure is then supplied by the surface

pump 10 through the power tubing 11, flowing downwardly therethrough and carrying with it loose sand, iron oxide, wax, and other foreign materials that may be washed by the operating fluid from the inner walls of the power tubing. Such operating fluid flows downwardly through the annular space 21 and fills the trapping space 23. It then flows through the upper filter member 46 and the ports 45 and downwardly through the interior of the filter element 20 into the fluid-operated pump 24, to actuate the latter. Such operating fluid also flows through the lower filter member 51 and the perforations 50 and combines with the flow through the filter element 20. Substantially all of the solid foreign material entrained in the operating fluid is thus caught on the outside of the filter members 46 and 51, permitting only clean operating fluid to flow to the fluid-operated pump 24. Additional quantities of such solid foreign materials settle out of the operating fluid and downwardly into the trapping space 23 where they are collected. As will be understood, the supply of operating fluid to the fluid-operated pump 24 causes it to discharge well fluid into the production tubing 13 and to pump it upwardly to the surface of the ground.

As operating fluid flows through the filter members 46 and 51 such solid foreign materials are deposited on the surface of the filter members and embedded therein, which causes a reduction in the fluid permeability of the filter members, with an attendant rise in fluid pressure in the interior of the tubular shell 18. Such rise in fluid pressure continues until the force exerted thereby on the upper face of the blow-out disk 38 is sufficient to break and rupture the blow-out disk, at which time operating fluid can then flow from the interior of the shell through the longitudinal slots 30 and the tubular stem 28 and downwardly through the by-pass element 19 and the interior of the filter element 20 to the fluid-operated pump 24. Upon rupture of the blow-out disk 38, obviously, fluid pressure inside the shell 18 drops, and thereafter no operating fluid, or at the most very little, flows through either of the filter members 46 or 51, the entire flow being directly through the by-pass element which, it will be understood, is in effect in parallel with the filter members. The broken portion of the blow-out disk 38 is caught and retained by the filter plate 40, which prevents any large portion of the blow-out disk from passing into the fluid-operated pump 24. Also, the perforations 41 in the filter plate 40 are sufficiently small to filter from the operating fluid passing therethrough any relatively large particles of foreign materials, which acts as a further protection for the fluid-operated pump 24. The perforations 41 are not, however, sufficiently small to impress any substantial fluid pressure differential thereacross.

The characteristics of the filter members 46 and 51 are so related to the breaking strength of the blow-out disk 38 that the blow-out disk will not break or rupture until sufficient operating fluid has passed through the power tubing 11 to clean from it most of the loose foreign material adhering to the inner wall thereof and depositing such foreign material in the trapping space 23 or on the filter members. Consequently, when the blow-out disk 38 finally ruptures, the concentration of foreign material in the operating fluid is sufficiently low that it passes through the fluid-operated pump 24 without injuring the same. As pointed out above, the blow-out disk 38 may be ruptured at will at any time by simply increasing the volume of the operating fluid as

delivered by the surface pump 10. This controlled breaking of the blow-out disk 38 may be desired in some instances, although normally automatic breaking thereof due to a rise in pressure of the operating fluid following a clogging of the filter members 46 and 51 will be preferred. Also, as will be appreciated, delaying the entrance of operating fluid directly from the power tubing 11 into the fluid-operated pump 24 will permit a new pump to wear itself in by operation to a substantial extent before any solid foreign material is allowed to enter the same. This is an added advantage.

The foregoing explanation will be adequate to permit one skilled in the art to practice readily the invention under varying conditions encountered in well production. However, for the purpose of illustration, more detailed information as to a specific installation is given herewith. In a well in which the fluid-operated pump has an average lift of about 3500 feet the pressure of the operating fluid in the power tubing 11 will approximate 1750 pounds per square inch during normal operation of the pump. The blow-out disk 38 is preferably designed to rupture when installed at a fluid pressure differential thereacross of approximately 800 pounds per square inch. Consequently, in such an installation the pressure of the operating fluid in the supply tubing 11 must rise substantially before the blow-out disk 38 will rupture. For best operation, the filter members 46 and 51 are preferably designed so that at least all of the initial fluid contents of the power tubing 11 can pass through the filter members before the fluid-pressure rise will rupture the blow-out disk 38. For a fluid-operated pump having a capacity of about 175 barrels per day, supplied with operating fluid through a power tubing having an internal diameter of $\frac{3}{4}$ inch and 3500 feet long, all of the initial contents of the power tubing will pass through the filter members in about 19 minutes. Therefore, in such an installation the filter members 46 and 51 are preferably designed to pass operating fluid therethrough for at least 19 minutes before the fluid-pressure rise will rupture the blow-out disk 38, which will eliminate most of the free detrimental foreign material from the operating fluid. As will be appreciated, however, the actual elapsed time required for such pressure rise in any particular installation depends upon the amount of free solid foreign material in the power tubing 11, and the rate at which operating fluid is supplied and this will vary greatly in practice from well to well and even from time to time in the same well.

Although we have shown and described a preferred embodiment of the invention, it will be understood that certain parts and elements thereof can be substituted by other parts and elements performing the same functions without departing from the spirit of the invention, and, consequently we do not intend to be limited to the specific embodiments described but desire to be afforded the full scope of the following claims.

We claim:

1. In a fluid-operated pumping device, the combination of: a fluid-operated pump adapted to be disposed in a well; means for receiving pumped fluid from said pump and conveying it upwardly through the well; supply means adapted to be disposed in said well and adapted to convey an operating fluid downwardly therethrough to operate said pump; filter means connecting said

supply means and said pump and adapted to filter operating fluid passing therethrough to said pump; and by-pass means connecting said supply means and said pump, in parallel with said filter means, said by-pass means being normally closed but adapted to open in response to a predetermined rise in fluid pressure in said supply means to permit operating fluid to flow through said by-pass means to said pump without passing through said filter means.

2. In a fluid-operated pumping device, the combination of: a fluid-operated pump adapted to be disposed in a well; production tubing for receiving pumped fluid from said pump and conveying it upwardly through the well; power tubing adapted to be disposed in said well and adapted to convey an operating fluid downwardly therethrough to operate said pump; and a combined filter and by-pass means disposed in said power tubing and forming a fluid connection between said power tubing and said pump, including a filter element adapted to filter operating fluid flowing therethrough from said power tubing to said pump, and a by-pass element in parallel with said filter element and being normally closed but adapted to open in response to a predetermined rise in fluid pressure in said power tubing to permit operating fluid to flow through said by-pass element to said pump without passing through said filter element.

3. In a fluid-operated pumping device, the combination of: a fluid-operated pump adapted to be disposed in a well; production tubing for receiving pumped fluid from said pump and conveying it upwardly through the well; power tubing adapted to be disposed in said well and adapted to convey an operating fluid downwardly therethrough to operate said pump; and a combined filter and by-pass means disposed in said power tubing and forming a fluid connection between said power tubing and said pump, including a filter element adapted to filter operating fluid flowing therethrough from said power tubing to said pump, and a by-pass element in parallel with said filter element and being normally closed but adapted to open in response to a predetermined rise in fluid pressure in said power tubing to permit operating fluid to flow through said by-pass element to said pump without passing through said filter element, said combined filter and by-pass means being removable as a unit from said power tubing.

4. In a fluid-operated pumping device, the combination of: a fluid-operated pump adapted to be disposed in a well; production tubing for receiving pumped fluid from said pump and conveying it upwardly through the well; power tubing adapted to be disposed in said well and adapted to convey an operating fluid downwardly therethrough to operate said pump; and a combined filter and by-pass means disposed in said power tubing and forming a fluid connection between said power tubing and said pump, said combined filter and by-pass means including tubular means having a radial opening therein, a filter element registering with said opening and adapted to filter operating fluid flowing therethrough from said power tubing, and a by-pass element in the upper portion of said tubular means adapted to normally close fluid communication between said tubular means and said power tubing but adapted to open in response to a predetermined rise in fluid pressure in said power tubing to permit operating fluid to flow through said tubular means

to said pump without passing through said filter element.

5. In combination with a fluid-operated pump: tubular shell means adapted to be disposed in a well and connected between a power tubing and said fluid-operated pump; filter means in said tubular shell means and adapted to filter operating fluid flowing therethrough; and by-pass means in said tubular shell means in parallel with said filter means, said by-pass means being normally closed but adapted to open in response to a predetermined fluid pressure exerted thereon to permit operating fluid to flow therethrough and through said tubular shell means without passing through said filter means.

6. In a device for use in a well in combination with a fluid-operating pump, the combination of: tubular shell means adapted to be disposed in a well and connected between a power tubing and a fluid-operated pump; tubular filter means in said tubular shell means and radially spaced therefrom and adapted to filter operating fluid flowing therethrough; and by-pass means in said tubular shell means above said filter means and in parallel with said filter means, said by-pass means including frangible means adapted to be broken in response to a predetermined fluid pressure exerted thereon to permit operating fluid to flow therethrough and through said tubular shell means without passing through said filter means.

7. In a device for use in a well in combination with a fluid-operated pump, the combination of: tubular shell means adapted to be disposed in a well and connected between a power tubing and a fluid-operated pump; filter means in said tubular shell means and adapted to filter operating fluid flowing therethrough; and by-pass means in said tubular shell means in parallel with said filter means, said by-pass means being normally closed but adapted to open in response to a predetermined fluid pressure exerted thereon to permit operating fluid to flow therethrough and through said tubular shell means without passing through said filter means, said by-pass means including a frangible plug which normally prevents flow through said by-pass means and which is adapted to be broken by a predetermined fluid pressure exerted thereon.

8. In a device for use in a well in combination with a fluid-operated pump, the combination of: tubular shell means adapted to be disposed in a well and connected between a power tubing and a fluid-operated pump; tubular filter means in said tubular shell means and radially spaced therefrom and spaced a substantial distance above the lower end of said tubular means and adapted to filter operating fluid flowing therethrough, the space between said filter means and said tubular means providing a trap for the collection of foreign materials; and by-pass means in said tubular shell means in parallel with said filter means, said by-pass means being normally closed but adapted to open in response to a predetermined fluid pressure exerted thereon to permit operating fluid to flow therethrough and through said tubular shell means without passing through said filter means.

9. In a device for use in a well in combination with a fluid-operated pump, the combination of: a tubular shell adapted to be disposed in a well and connected between a power tubing and a fluid-operated pump; tubular means within said shell and closing the lower end of said shell, said tubular means having an opening therein adapted to provide fluid communication between the in-

terior of said shell and the interior of said tubular means; a filter element registering with said opening and adapted to filter fluid passing from said interior of said shell to said interior of said tubular means; and by-pass means disposed in said tubular means above said opening, said by-pass means being normally closed but adapted to open in response to a predetermined rise in fluid pressure in said interior of said shell to permit operating fluid to flow therethrough and through said tubular means without passing through said filter means.

10. In a device for use in a well in combination with a fluid-operated pump, the combination of: a tubular shell adapted to be disposed in a well and connected between a power tubing and a fluid-operated pump; tubular means within said shell and closing the lower end of said shell, said tubular means having an opening therein adapted to provide fluid communication between the interior of said shell and the interior of said tubular means; a filter element registering with said opening and adapted to filter fluid passing from said interior of said shell to said interior of said tubular means; and a frangible plug disposed in said tubular means above said opening, said frangible plug being normally closed but adapted to open in response to a predetermined rise in fluid pressure in said interior of said shell to permit operating fluid to flow therethrough and through said tubular means without passing through said filter means.

11. In a device for use in a well in combination with a fluid-operated pump, the combination of: a tubular shell adapted to be disposed in a well and connected between a power tubing and a fluid-operated pump; tubular means within said shell and closing the lower end of said shell, said tubular means having an opening therein adapted to provide fluid communication between the interior of said shell and the interior of said tubular means; a first filter element registering with said opening and adapted to filter relatively fine foreign material from fluid passing from said interior of said shell to said interior of said tubular means; by-pass means disposed in said tubular means above said opening, said by-pass means being normally closed but adapted to open in response to a predetermined rise in fluid pressure in said interior of said shell to permit operating fluid to flow therethrough and through said tubular means without passing through said filter means; and a second filter element disposed in said tubular means between said opening and said by-pass means and adapted to filter relatively coarse

foreign material from fluid passing therethrough.

12. In a fluid-operated pumping device, the combination of: a fluid-operated pump adapted to be disposed in a well; means for receiving pumped fluid from said pump and conveying it upwardly through said well; supply means adapted to be disposed in said well and adapted to convey an operating fluid downwardly therethrough to operate said pump; filter means between said supply means and said pump for filtering operating fluid flowing to said pump from said supply means; and means for rendering said filter means inoperative when the permeability of filter means drops to a predetermined value and simultaneously permitting a flow of operating fluid from said supply means to said pump without passing through said filter means.

13. In a fluid-operated pumping device, the combination of: a fluid-operated pump adapted to be disposed in a well; means for receiving pumped fluid from said pump and conveying it upwardly through the well; supply means adapted to be disposed in the well and adapted to convey an operating fluid downwardly therethrough to operate said pump; filter means connecting said supply means and said pump and adapted to filter operating fluid passing therethrough to said pump; and by-pass means connecting said supply means and said pump in parallel with said filter means, said by-pass means including frangible means adapted to be broken in response to a predetermined rise in fluid pressure in said supply means to permit operating fluid to flow in parallel with said filter means to said pump.

14. A fluid-operated pumping device as set forth in claim 13 including a filter for coarse material connected in parallel with said filter means and connected in series with said frangible means downstream therefrom, said filter being adapted to intercept pieces of said frangible means upon breaking thereof.
